UNITED STATES PATENT OFFICE.

ARTHUR EARLY HARRISON, OF DANDRIDGE, TENNESSEE.

VENDING APPARATUS.

No. 842,783.

Specification of Letters Patent.

Patented Jan. 29, 1907.

Application filed May 9, 1906. Serial No. 315,907.

To all whom it may concern:

Be it known that I, ARTHUR E. HARRISON, a citizen of the United States of America, residing at Dandridge, in the county of Jefferson and State of Tennessee, have invented new and useful Improvements in Vending Apparatus, of which the following is a specification.

This invention relates to improvements in automatic vending apparatus of that type employing a rotary carrier to hold or contain the goods to be vended, said carrier being intermittently operated by a coin-controlled actuating device, so as to discharge or expose for removal a desired article, number of articles, or quantity of goods at each successive operation.

The object of the invention is to provide a simple and efficient construction of apparatus of this character wherein improved means are provided for controlling the operation of the carrier.

In the accompanying drawings, Figure 1 is an irregular vertical longitudinal section 25 through the apparatus, taken on line $x-x$ of Fig. 2. Fig. 2 is a horizontal section. Fig. 3 is a vertical section on line $y-y$ of Fig. 2. Fig. 4 is a perspective view of the plunger. Fig. 5 is a rear elevation of the same. Fig. 6 30 is a perspective view of the carrier-controlling dog. Fig. 7 is a detail section through one side of the casing looking toward the dog and its guideway.

Referring to the drawings, the numeral 1 35 designates the casing of the apparatus provided at its upper front portion with a transparent panel 2 and below the same with an opening 3 for the removal of the article or goods from the carrier. The carrier comprises a drum or wheel 4, provided with a series of peripheral pockets or chambers 5, adapted to hold the article or goods to be vended. These pockets are adapted during the intermittent rotation of the drum to be 45 successively brought into alinement with the opening 3, so that the purchaser may extract the article or goods therefrom. The carrier is mounted upon a rotary shaft or axle 5, suitably journaled in the casing, and is provided upon its side edges with peripheral ratchet-teeth 6, adapted to be engaged by pawls 7 upon the base of a chamber or casing 8 at the front of the machine below the opening 3, said teeth and pawls being properly 55 formed to permit the carrier to have forward

rotation, while preventing retrograde rotation thereof.

A curved plate 9 incloses the lower portion of the carrier and is fixed at its front end to the bottom of the casing 8 and at its rear end 60 to a stationary cross-strip 10, said plate forming a closure for the pockets on the lower portion of the wheel to prevent the goods contained therein from dropping out.

Within the chamber 8 is mounted a sliding 65 plunger 11, comprising an oblong rectangular block having an upper horizontal front portion 12, to which is attached a rod or stem 13, leading outward through the front wall of the casing and provided with a push-button or knob 14. A coiled spring 15 surrounds the stem between the button and front wall of the casing and is inclosed at its inner end in a guide-tube 16, the function of said spring being to retract the plunger after 70 its release by the purchaser and the operation of the machine for the purchase of an article or package of goods.

The block 11 is formed with a slot or recess 17, in which is arranged a coin-bracing 80 rib 18, and at the rear of said rib is a vertical slot 19, formed in the front edge of the flange 12, which slot is adapted to normally align with the coin-inlet 20. The coin inserted through said inlet drops downward through 85 the slot 19 and rests partially therein and partially upon the bottom wall 21 of the casing 8. The upper portion of the coin bears against the rib 18 and is held thereby from tilting when the plunger is pushed forward. 90 The wall 21 is formed with a slot 22 for the discharge of the coin into the casing, and arranged upon said wall is a spring dog or detent 23. When the plunger is forced to the limit of its forward movement, the lower 95 edge of the coin rides over this detent, which springs upward in rear of the coin and prevents its withdrawal and retraction of the plunger in the event that the coin should hang in the slot 22, so that the purchaser by 100 proper manipulation of the knob 14 may effect the release of the coin, so that it will pass downward through the slot. The detent 23 also prevents any possibility of the return of the coin with the plunger after the 105 latter has been operated to turn the carrier-drum. The plunger is formed in its lower edge with an opening 24 to clear the detent 23, and the flange 12 thereof is formed in its upper edge with a notch 25, having a beveled 110

bottom wall. Pivotaly supported upon the top wall of the casing 8 is a guard-dog 26, having a beveled front end 27, a series of notches 28 adjacent thereto, and a stop-arm 29, which limits the downward movement of its beveled and notched portion. The notches 28 are of such size as to permit a coin of the desired denomination to readily tilt the plunger upward and pass the same, while causing the plunger to engage the edges of thinner tokens or coins of less denomination to prevent the same from being fed forward, the insertion of an improper coin thereby causing the plunger to be locked against forward movement.

The rear face of the plunger is transversely grooved to loosely receive and bear against a transverse cross-bar 30, provided at its ends with arms 31 and 32, located on opposite sides of the casing and extending toward the rear thereof, the arm 32 being slidably mounted in a suitable bearing 33. The said cross-bar and arms form a sliding frame for effecting the operation of the carrier-drum. The arm 31 extends below a guide 34 and through a chamber or cylinder 35, and fixed to said arm and operating in said cylinder is a piston 36. This cylinder and piston form an air-cushion to check the rearward movement of the sliding frame and to prevent too forcible or violent operation thereof.

On the shaft of the drum at one side of said drum is a gear-wheel 37, meshing with a drive-gear 38, loosely mounted on a suitably-supported shaft 39, having a rectangular key-receiving end 40. A coiled spring 41 is fixed at one end to the shaft and at the other end to said gear and imparts rearward motion thereto to communicate reverse motion to the gear 37, whereby the carrier-drum is adapted to be rotated in a forward direction. Any suitable pawl-and-ratchet mechanism may be provided to hold the gear 38 from retrograde rotation. The spring 41 may be wound at intervals by the application of a key to the end 40 of the shaft 39, and in practice the spring may be of such construction as to impart one complete rotation only to the drum before rewinding thereof is required.

The drum is provided on its side opposite the spring-driving mechanism with a series of pins or projections 42, extending laterally therefrom and equal in number to and coinciding in arrangement with the pockets 5. These pins are adapted to be engaged by a controlling-dog 43. The dog 43 comprises a rectangular block suitably fixed to the arm 31 and formed at its outer side with a dovetailed projection 44, engaging a dovetailed slot in the guide or casing 34. In the block are formed slots or passages 45 46, opening laterally through the same on its inner side or the side opposite the projection 44. The slot 45 is arcuately curved and connects at its lower forward end with the front end of

the slot 46, a shoulder 47 thus being formed at the point of intersection of said slots. At its upper end the slot 45 has an obliquely-arranged inlet 48, formed with a beveled seat-wall 49, extending upwardly and rearwardly therefrom. The slot 46 extends horizontally and opens through the rear of the dog beneath and in advance of the seat-wall 49. The lower rear portion of the block is cut away to shorten the slot 46 and is beveled to provide for the proper application thereto of an obliquely-arranged spring-detent 50, guarding the rear or outlet portion of said slot. This construction provides an overhanging stop-shoulder 51 above and in rear of the outlet end of the slot. The dog normally engages one of the pins 42, which seats therein at the point of intersection of the two slots and rests against the shoulder 47, whereby the drum is held from movement with an empty pocket facing the discharge-opening 3.

The operation is as follows: Upon the insertion of a coin into the slot 19 the inserted coin will lie in rear of the cross-arm 30 of the sliding frame, and thereby couple the same to the plunger 11, so that upon the forward motion of said plunger the sliding frame will be operated to communicate motion to the dog 43. Upon such forward motion of the dog 95 the pin 42, occupying the slot 46, will pass outward at the rear of said slot and beyond the detent 50, which latter again closes the slot after the passage of the pin to prevent the dog from being retracted until the full operation is carried out. During this forward movement of the dog the pin 43 of the next adjacent superposed pocket will ride over the upper face of the dog and engage the seat portion 49, thus allowing said pin to enter the slot 45. The drum will thereby be free for movement and the spring-driving mechanism will impel it forward, such motion being controlled for the rotation of the drum to the extent of a single pocket by the movement of such superposed pin downward in the curved slot 45, whereby upon the release of the plunger and its restoration to normal position the action of the pin in riding in the slot 45 will shift the sliding frame back to normal position and the pin will move into engagement with the stop-shoulder 47, thus holding the drum from further revolution. This operation brings the filled pocket above and in rear of the opening 3 into alignment with said opening, so that the article or goods may be extracted therefrom by the purchaser.

It will thus be seen that my invention provides a simple and effective vending apparatus of the character described which embodies improved means for controlling the action of the drum, the operation of the plunger, and the positive movement of the drum to a prescribed position upon each operation of the plunger. The apparatus may be con-

structed in practice of any desired size and provided with any preferred number of pockets and may be modified in other respects to suit different requirements of service.

5 Having thus described the invention, what is claimed as new is—

1. In a vending apparatus, the combination of a spring-actuated carrier provided with locking projections, a sliding frame, a dog fixed to and movable with the sliding frame and provided with receiving and releasing slots coöperating with said projections to control the movement of said carrier, and means for actuating the sliding 15 frame.

2. In a vending apparatus, the combination of a rotary spring-actuated carrier provided with locking projections, a sliding frame, a dog carried by said sliding frame 20 and having receiving and releasing slots coöperating with said projections to control the movement of the carrier, a detent upon the dog guarding the releasing-slot, and means for actuating the sliding frame.

25 3. In a vending apparatus, the combination of a rotary spring-actuated carrier, locking projections upon the carrier, a dog arranged to slide in a fixed plane and provided with an arcuate receiving-slot and an intersecting releasing-slot coöperating with said projections to control the movement of the carrier, and means for operating the dogs.

4. In a vending apparatus, the combination of a rotary spring-actuated carrier, locking projections upon the carrier, a dog arranged to slide in a fixed path and provided with an arcuate receiving-slot and an intersecting releasing-slot coöperating with said projections to control the movement of the carrier, said dog being further provided at the outlet end of said releasing-slot with a detent, and means for actuating the dog.

5. In a vending apparatus, the combination of a rotary spring-actuated carrier provided with locking projections, a sliding dog movable across the path of movement of said projections, said dog being provided with intersecting arcuate and horizontal receiving and releasing slots coöperating with said projections to control the movement of the carrier, said receiving-slot being provided with an inlet having an inclined guide and the releasing-slot with a detent at the outer end thereof, and means for actuating the dog.

55 6. In a vending apparatus, the combination of a rotary spring-actuated carrier provided with locking projections, a sliding frame, a dog carried by the frame and movable across the path of rotation of said projec-

tions, said dog being provided with intersecting arcuate and straight receiving and releasing slots coöperating with said projections to control the movement of the carrier, said receiving-slot being provided with a guide-inlet and the releasing-slot with a detent at the outlet end thereof, and means for imparting motion to the sliding frame.

7. In a vending apparatus, the combination of a rotary spring-actuated carrier provided with locking projections, a sliding dog comprising a block having an arcuate receiving-slot provided with an inlet at its upper end and a horizontal receiving-slot intersecting said arcuate slot at its forward end and opening at its rear end through the block, 70 said slots extending through one side of the block to receive and coöperate with said projections to control the movement of the carrier, a detent at the outlet end of the releasing-slot, and means for imparting motion to the 75 dog.

8. In a vending apparatus, a rotary spring-actuated carrier provided with a circular series of locking projections, in combination with a dog comprising a block having receiving and releasing slots, said slots being arranged to release a projection fitting therein and receive the succeeding projection upon the forward movement of the block to permit the carrier to rotate the distance between adjacent pins, and means for imparting motion to the dog.

9. In a vending apparatus, the combination of a spring-actuated rotary carrier provided with locking projections, the dog coöperating with said locking projections to control the movement of the carrier, said dog being provided with receiving and releasing slots coöperating with said projections, a sliding frame carrying the dog, cushioning means associated with said frame, and means for operating the sliding frame.

10. In a vending apparatus, the combination of a rotary spring-actuated carrier provided with locking projections upon one side thereof, a sliding frame, a dog carried thereby having receiving and releasing slots opening through one side thereof and coöperating with said projections to control the action of the carrier, and means for imparting motion to the sliding frame.

In testimony whereof I affix my signature in presence of two witnesses.

ARTHUR EARLY HARRISON.
